UNITED STATES PATENT OFFICE.

ALLEN A. BOWSER, OF FORT WAYNE, INDIANA, ASSIGNOR TO S. F. BOWSER & COMPANY, OF FORT WAYNE, INDIANA, A CORPORATION OF INDIANA.

CAP FOR FILL-PIPES, &c.

No. 875,689.

Specification of Letters Patent.

Patented Jan. 7, 1908.

Application filed June 23, 1906. Serial No. 323,044.

To all whom it may concern:

Be it known that I, ALLEN A. BOWSER, a citizen of the United States, residing at Fort Wayne, in the county of Allen and State of Indiana, have invented certain new and useful Improvements in Caps for Fill-Pipes and the Like, of which the following is a full, clear, and exact specification.

This invention relates to caps for the fill-pipes of gasoline or oil tanks, and in fact, fill-pipes where it is desirable to close the inlet to a tank or chamber, and the invention has for its object to provide an improved and simple form of cap for a fill-pipe which will effectually close the pipe against the admission of rain or dirt, and at the same time will provide for the free discharge of any excess of gas, as well as for the inlet of air necessary to take the place of the liquid being extracted, the device being also proof against being removed by unauthorized persons.

With a view to the attainment of these ends, and the accomplishment of certain other objects which will hereinafter appear, the invention consists in the features of novelty which will now be described with reference to the accompanying drawing, showing an exemplification of the invention, and will then be particularly pointed out in the claims.

In the said drawing—Figure 1 is a vertical sectional view on the line 1, 1, Fig. 2, and Fig. 2 is a plan section on the line 2, 2, of Fig. 1.

1 is the top of the tank or chamber having the fill-pipe to be closed, which is shown in this example as being a threaded pipe or nipple 2. Upon this pipe or nipple is screwed the cap whose body portion is indicated at 3, and which when screwed into place completely closes the pipe 2, with the exception of a vent 4 in which is fitted a valve housing 5, carrying or being provided with any suitable means of permitting the excess of gas to blow off and the ready entrance of air to take the place of the liquid withdrawn. Such a means may consist of two ball-valves 6, 7, the former of which closes a valve or vent passage 8, and is held against its seat by a spring 9, secured in place by any suitable bushing 10. Extending outwardly from the housing 5 is a neck 11, in which the seat for the valve 7 is formed, the latter being held in place in any appropriate way, as by means of a perforated cap 12. The cap thus

formed is provided with means for locking it in place, consisting preferably of a hasp 13, hinged at 14 to the body 3, and having on the opposite side a downwardly projecting arm 15, which when the hasp is down in place engages with a boss 16 formed on the side of the fill-pipe 2, and consequently prevents the cap body from being removed by unscrewing. This hasp 3 is provided also with an aperture 17 through which protrudes a staple 20, attached to the body 3 in any suitable way, as by means of a screw-threaded stem 21, the aperture 17 being narrow like the width of the staple 20, so that when the hasp is in place over the staple, the staple cannot be unscrewed, the eye of the staple projecting sufficiently for the passage of a pad-lock, or other suitable locking means. The hasp 13 also serves as a cover for the vent 4, which, as indicated in Fig. 1, is formed with a surrounding flange 22, to prevent any water, which may leak in under the hasp, from running through the vent 4, and the under side of the hasp is formed with a recess 23 to receive this flange.

I claim:

1. In a device for the purpose described, the combination of a fill-pipe, a cap body, said fill-pipe and cap body being provided with coöperative means for attachment of the body to the pipe by a relative rotary movement, means for holding the parts against said relative rotary movement, embodying two disengageable members, one carried by the cap body and the other having a fixed relation to the fill-pipe, and means for holding said members from being disengaged.

2. In a device for the purpose described, the combination of a fill-pipe, a cap body, said cap body and fill-pipe being provided with means for attaching them together requiring a relative rotary movement, a hasp carried by the body, means fixed with relation to the fill-pipe for the engagement of the hasp, for holding the body against rotary movement, and means for locking the hasp and body against relative movement.

3. In a device for the purpose described, the combination of a fill-pipe, a cap body for closing the same, said cap body and fill-pipe having means for attaching them together, requiring a relative rotary movement, a hasp hinged to the body and having a projection, means fixed with relation to the fill-

pipe for the engagement of said projection, and means for locking the hasp against pivotal movement on its hinge.

4. In a device for the purpose described, 5 the combination of a fill-pipe, a cap body, said body and pipe having means of attachment requiring a relative rotary movement, a hasp carried by the body, means fixed with relation to the fill-pipe for the engagement of 10 the hasp for holding the body against said relative rotary movement, and a staple for a lock screwed into the body and held from unscrewing by the hasp.

5. In a device for the purpose described, 15 the combination of a fill-pipe, a cap body, means for attaching the body and pipe together, requiring a relative rotary movement, a slotted hasp carried by the body, means fixed with relation to the pipe, and engaging with a part of the hasp, for holding 20 the body against said relative rotary movement, and a staple screwed into the body and projecting through the slot of the hasp, for receiving a lock.

25 6. In a device for the purpose described, the combination of a fill-pipe, a cap body thereon having a single vent opening, a valve housing communicating with said vent, two valves in said housing, opening in oppo-

sition directions with respect to internal pressure in the fill-pipe, and means for yieldingly holding the outwardly-opening one of said valves to its seat.

7. In a device for the purpose described, 30 the combination of a fill-pipe, a cap body 35 removably attached thereto, and provided with a vent, and locking means for holding the cap body against removal, embodying a member carried by the cap body, and covering said vent.

8. In a device for the purpose described, 40 the combination of a fill-pipe, a cap body removably secured thereto and provided with a vent, said vent having a surrounding flange on the exterior of the body, and means for 45 locking the cap body against removal, embodying a member secured to the body and having a recess in its under side fitting over said flange.

In testimony whereof I have signed my 50 name to this specification; in the presence of two subscribing witnesses, on this 18th day of June A. D. 1906.

ALLEN A. BOWSER.
